STAND FOR HOLDING INTRAVENOUS FLUID CONTAINERS

Dennis Arblaster, 34081 La Serena,
Dana Point, Calif. 92629

Filed Feb. 2, 1966, Ser. No. 961

Term of patent 14 years

(Cl. D83—1)

FIG. 1.

FIG. 2.

FIG. 1 is a stand for holding intravenous fluid containers, embodying my new design, the broken line illustration representing the fluid containers is shown for illustrative purposes only; and

FIG. 2 is a top plan view thereof, the broken line four-legged conventional base support disclosed in FIG. 1 has been omitted for ease of illustration.

The dominant features of my design reside in the portions shown in full lines.

I claim:

The ornamental design for a stand for holding intravenous fluid containers, as shown and described.
